(57) **CLAIM**

The ornamental design for a bowl for an ice cream maker as shown and described.

DESCRIPTION

FIG. 1 is a perspective view of a bowl for an ice cream maker according to the design;

FIG. 2 is a front elevation view thereof, a back elevation view thereof being identical to the front elevation view;
FIG. 3 is a right side elevation view thereof, a left side elevation view thereof being identical to the right side elevation view;

FIG. 4 is a top plan view thereof; and,
FIG. 5 is a bottom plan view thereof.

The portions of the article shown in even broken line form no part of the claimed design.

Dash-dot-dash broken lines adjacent un-shaded areas represent bounds of the claimed design and form no part of the claimed design themselves.
